GANG PUNCH

Nelson S. Welk, Athens, Ohio, assignor to The
McBee Company, Athens, Ohio, a corporation
of Ohio

Application July 12, 1948, Serial No. 38,312
5 Claims. (Cl. 164—91)

1

This invention relates to a gang punch; more particularly, to a gang punch which is operable to punch marginal perforations and notches in cards, checks and the like.

Record and statistical cards, checks and other paper records and documents are frequently provided with marginal perforations to enable coding to be notched into their marginal edges. Such cards or sheets are coded for classification by notching the cards marginally to provide an open notch or slot extending from the edge of the card to one or more of the marginal perforations. A group of cards, checks or the like so coded and classified may be sorted by means of sorting needles or rods, which are extended through the marginal perforations in a manner which is well-known.

In a sizable installation where it is necessary to punch and notch large numbers of such cards, etc., it is desirable to employ a gang punch which is effective to punch a plurality of marginal perforations or notches in one or more cards in one punching operation. It is further desirable that the gang punch be readily adjustable to inactivate one or more of the punching elements as desired.

It is an object of the invention to provide an improved form of gang punch.

It is a further object of this invention to provide an improved form of gang punch for marginally perforating or notching record and statistical cards, checks and the like.

It is a still further object of the invention to provide a gang punch including a plurality of spaced punching members, each of which can be inactivated to vary the pattern of punching as desired.

These and other objects of the invention will be apparent from the ensuing description and the appended claims.

One form which the invention may assume is exemplified in the following description and illustrated by way of example in the accompanying drawings, in which:

Fig. 1 is a vertical, transverse section of the machine, taken along the line 1—1 of Fig. 2.

Fig. 2 is a horizontal section taken along the line 2—2 of Fig. 1, and with certain parts broken away to reveal other parts more clearly.

Referring now to the drawings, a housing 1 is provided having pads 2 and 3 secured to the bottom thereof, and a longitudinal bottom opening 4, and having a die support 5 at the forward portion of the machine and a removable cover 6 pivotally secured to the rearward portion of the housing by means of ears 10 and pivot screws 11.

A stout shaft 12 of uniform diameter is provided, being journaled in bearings 13 formed in the side walls of the housing, and a plurality of

spaced male punching dies 14 are rotatably mounted on the shaft 12. A female die plate 15 is also provided, being secured to the die support 5 by rivets 16. The die plate 15 is slotted at its inner edge to provide teeth 17 and slots 18, thus providing a female die. An edged guide 19 is provided, being secured to the female die and adjustable relatively thereto by means of a screw 20 and a slot 21.

The shaft 12 is actuated by means of a pair of operating levers 26 secured, as by set screws 27, to the ends of the shaft 12 and joined at their outer ends by a bar 28. The operating levers 26 extend rearwardly of the shaft 12 and are secured to a bail member 29. The bail member 29 is of generally U-shape, having ears or legs 30 pivotally supported by the operating levers 26 by means of pivot screws 31, and a base portion 33 having a rearwardly extending flange 33a. Each ear 30; hence also the whole bail member 29; is urged in counterclockwise direction by a coil spring 34 secured at 35 to the ear and at 36 to the housing.

Each male die 14 is of flat, disc-like configuration, and it is provided with a punching blade 40, an abutment portion 41 of circular radius, and a radial notch 43 defined by radial projections 46 and 47. Proper spacing of the dies 14 is obtained by means of an upper comb or guide 48 having teeth 49 and slots 50 and a lower comb 51 having teeth 52 and slots 53. The several dies 14 are received within the slots 50 and 53, and also within the slots 18 of the female die, which thus serve as guides and spacers as well as dies.

It will be seen that, with the base 33 of the bail member 29 received within the notches 43 of the male dies 14, as the bar 28 is depressed, the bail base 33 will abut the projections 46, thus rotating the male dies counter-clockwise to punch marginal notches in a card or the like. When the bar 28 is released, the springs 34 will return the dies 14 and the bail 29, operating levers 26 and bar 28 to their original position. The circular abutment portion 41 of the male dies serves as a gauge to gauge the depth of notching, and the edged guide 19, which is adjustable to vary the endwise position of the cards, etc., being punched, serves to guide and align the cards. Cuttings can be removed through the bottom opening 4.

Should it be desired to inactivate one or more male dies 14, as, for example, to vary the notching of marginally punched cards, the rear cover 6 is pivoted rearwardly, the bail member 29 is then pivoted rearwardly, as by inserting a finger underneath the flange 33a and pulling to clear the notches 43, and those dies 14 which are to be inactivated are rotated clockwise until the bail base 33 is disposed on the opposite side of the projection 46. The bail member is then released

to pivot back to its original position, the cover 6 closed, and the machine is in readiness for use, with certain dies 14 inactivated in accordance with the desired punching pattern.

Should it be desired to punch holes instead of notches, or to punch notches of greater or lesser depth or of different shape, the machine is easily modified to fulfill the new requirements merely by substituting new male dies of the proper configuration. Such interchange of dies is facilitated by reason of the fact that the dies 14 are slideable along the shaft 12, being held in proper spaced relationship by the combs 48 and 51 and by the die plate 15. Merely by loosening the set screws 27 in the operating levers 26, and knocking out the shaft 12, the dies 14 may be removed and replaced.

It will thus be seen that a gang punch is provided which is simple of design and in operation, which is effective to punch a large number of holes or notches in one or more cards or the like, and which is easily adjustable to inactivate any of the individual male punching dies and to interchange sets of male dies.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A gang punch including a shaft, a plurality of punching members rotatably mounted on said shaft, each member having a notched portion, an operating lever mounted on said shaft for pivotal movement about the axis thereof, and an actuating member carried by the lever and engaging the notched portions on the members for causing movement of said members to and from an operative position, said actuating member being pivotally mounted on the lever for movement away from and toward said punching members whereby when said actuating member is moved away from said punching members, said punching members may be rotated to such a position that said actuating member will not engage said notched portions when said member is moved toward said members.

2. A gang punch including a shaft, a plurality of punching members rotatably mounted on said shaft, each member having a notched portion, an operating lever mounted on said shaft for pivotal movement about the axis thereof, an actuating member carried by the lever and engaging the notched portions on the members for causing movement of said members to and from an operative position, said actuating member pivotally mounted on the lever for movement away from the notched portions of the punching members, whereby the punching members can be rotated to such a position that when said actuating member is moved back toward said punching members it will not engage said notched portions, and resilient means constantly urging said actuating member toward said punching members.

3. A gang punch including a shaft, a plurality of punching members rotatably mounted on said shaft, an operating lever mounted for pivotal movement, and an actuating member carried by the lever for causing movement of said punching members to and from an operative position, said actuating member and said punching members

having interengaging portions establishing a driving connection between the actuating member and said punching members, said actuating member being pivotally mounted on the lever for movement away from said punching members, whereby when said actuating member is moved away from said punching members said members may be rotated to such a position that when said actuating member is moved back toward said members said interengaging portions will be out of registry and said members will not be actuated by the actuating member.

4. A gang punch including a shaft, a plurality of punching members rotatably mounted on said shaft, an operating lever mounted for pivotal movement, an actuating member carried by the lever for causing movement of said punching members to and from an operative position, said actuating member and said punching members having interengaging portions establishing a driving connection between the actuating member and said punching members, said actuating member being pivotally mounted on the lever for movement away from said punching members, whereby when said actuating member is moved away from said punching members said members may be rotated to such a position that when said actuating member is moved back toward said members said interengaging portions will be out of registry and said members will not be actuated by the actuating member, and resilient means constantly urging said actuating member toward said punching members.

5. A card punching device comprising a frame 35 having a female die plate, a shaft supported by said frame, a plurality of male die punching members rotatably mounted on said shaft, an operating lever pivotally mounted on said frame, an actuating member mounted on said lever for causing movement of said punching members to and from an operative position when said operating lever is actuated, said actuating member and said punching members having interengaging portions establishing a driving connection between the actuating member and said punching members, said actuating member being movably mounted on said lever for movement away from said punching members, whereby when said actuating member is so moved, said punching members may be rotated to such a position that when said actuating member is moved back toward said punching members said interengaging portions will be out of registry and said punching members will not be actuated upon actuation of said operating lever, and yieldable means constantly urging said actuating member toward said punching members.

NELSON S. WELK.
